By his Attorney
Makdon van Raastink,

UNITED STATES PATENT OFFICE.

REINHOLD KALFURST, OF CLEMENTON HEIGHTS, NEW JERSEY.

SEPARABLE NON-SLIPPING ATTACHMENT FOR SHOES.

1,284,703.

Specification of Letters Patent. Patented Nov. 12, 1918.

Application filed December 21, 1917. Serial No. 208,202.

To all whom it may concern:

Be it known that I, REINHOLD KALFURST, a citizen of the United States, residing at Clementon Heights, in the county of Cam-
5 den and State of New Jersey, have invented certain new and useful Improvements in Separable Non-Slipping Attachments for Shoes, of which the following is a specification.

10 My invention relates to improvements in means for preventing shoes from slipping and has as its principal object the provision of a separable attachment which may be readily applied to the heel of a shoe when-
15 ever desired and having separable means whereby the said attachment may be held firmly in position and yet readily removable.

I attain these and other objects by means of the novel design, construction and combination of parts hereinafter described and shown in the accompanying drawings, wherein,

Figure 1 is a side view showing the attachment in position on the heel of a shoe;

25 Fig. 2 is a plan view of the device;

Fig. 3 is a vertical sectional view of the device;

30 Fig. 4 is likewise a vertical sectional view of the device taken on the opposite side to Fig. 3;

Fig. 5 is a plan view of the locking bar, and Fig. 6 is an end view of the attachment, part thereof being broken away, illustrating a method of locking the device in position
35 by means of a screw.

Similar reference characters refer to similar parts throughout the drawings.

Referring to the drawings in detail the invention consists of a frame *a*, constructed
40 of a single sheet of suitable material, substantially of the contour illustrated and adapted to fit snugly over the heel of a shoe *o*. Formed integral therewith are the upwardly extending lugs or parts *b*, *c* and *d* as shown. The lugs *b* are so formed that they will grip tightly the corners of the heel, being made slightly beveled for that purpose in addition to being interiorly corrugated. The lugs or parts *c* and *d* are adapted to fit
45 firmly against the rear sides of the heel.

Apertures *e'*, substantially oblong in form, are cut out or stamped in the said frame *a*, as illustrated, the side portions thereof being bent and extended outwardly and down-
50 wardly forming a series of spurs *e*, said

spurs *e* extending in a horizontal position to said frame *a*. Apertures *f'*, substantially square in form, are likewise cut out or stamped in the said frame *a*, as illustrated, the end portions thereof being bent and ex- 60 tended outwardly and downwardly forming a series of spurs *f*, said spurs *f* extending in a parallel position to said frame *a*. Said spurs *e* and *f* projecting from said frame *a* an equal distance.

The lug *c* on the left side of the frame *a* is provided with the opening *c'* terminating in the rounded pocket *c*² as particularly illustrated in Fig. 4. A like opening *d*² is provided in the lug *d* on the right side of 70 said frame *a*, which likewise terminates in a rounded pocket *d*² as particularly illustrated in Fig. 3, the opening *c'* being cut vertically in the lug *c* and the opening *d*² being cut longitudinally in the lug *d*, the pockets *c'* 75 and *d*² being in parallel alinement to each other.

A separable horizontal locking bar *h* is provided as a preferred means for holding the device firmly in position on the heel. 80 Said bar *h* has the notches *i* and *p* on either side thereof and near the ends as illustrated, in order to engage the openings *c'* and *d*², and substantially in the center thereof and integral therewith the extending projection 85 *q* terminating in the prongs *j* and *k* to engage with the heel of the shoe.

A portion *l* of the frame *a* may be extended beyond the outer edge of said frame *a* as particularly illustrated in Fig. 6. This 90 extending portion *l* may be turned upwardly on a line paralleling the said outer edge of said frame *a* so that it will fit against the heel of the shoe and may be secured thereagainst by means of a screw *m* having the 95 screw head *n*, through a suitable opening in said portion *l*.

Openings *g* are also provided in the frame *a* as shown. Means may be inserted in said openings to secure the device to the underneath portion of the heel.

To secure the attachment in place after it is placed over the heel of the shoe, the parts *b* gripping firmly the corners of said heel and the lugs *c* and *d* the rear sides thereof, 105 the separable horizontal locking bar *h* is first inserted in the opening *c'* and then forced downwardly into the pocket *c*². The bar *h* is then turned by means of the notches *p* in the said pocket *c*² securely positioning same 110

therein thereby bringing the notches *i* in position to be inserted in the horizontal openings *d*² in lug *d*. The bar is then forced through said opening *d*² until it rests in the pocket *d*'. This action causes the prongs *j* and *k* to engage the outside end of the heel, thus securely locking the attachment in position. To disengage and remove said bar *h* the said bar is withdrawn from the pocket *d*' through the opening *d*², the prongs *j* and *k* withdrawn from the heel, the bar then being turned until it can be withdrawn from the pocket *c*² through the opening *c*'. Said bar *h* extends sufficiently beyond the outside limits of the heel to enable the operator to grasp an end thereof to disengage and remove it.

In lieu of said locking bar *h* the attachment may be held firmly in position on the heel by having a portion *l* thereof extend beyond the outside line of said device and then bending this portion *l* upwardly against the end of the heel and securing same thereagainst by means of a threaded screw through a suitable opening therein.

Having thus described my invention what

I claim as new and desire to secure by Letters Patent is:

A separable non-slipping attachment for shoes, comprising a frame, front and rear lugs integral with said frame for positioning the same on the heel of a shoe, a series of spurs projecting from and integral with said frame, a separable horizontal locking bar provided with a plurality of notches to engage openings in said rear lugs, said rear lugs having openings and terminating in pockets, said pockets paralleling and in alinement with each other, and a projection extending from and integral with said locking bar terminating in prongs, said prongs adapted to engage the rear portion of the said heel, whereby said locking bar may be secured in said pockets and on said heel to maintain said attachment in position on said heel.

In testimony whereof I affix my signature in presence of two witnesses.

REINHOLD KALFURST.
